FIG.9

1 CLEANING PAD

This application claims the benefit of U.S. Provisional Application Ser. No. 62/191,929 filed Jul. 13, 2015, which is hereby incorporated by reference for all that it discloses.

BACKGROUND

Modern cleaning pads for wood floor mops are typically rectangular in shape and are removably attached, as by a hook and loop fasteners, to a mop head of similar shape. A cleaning pad often includes a fabric that is attached to the mop head and a floor engaging fabric that is attached to the first fabric. One popular cleaning pad material for floor mops is microfiber because of its ability to trap and retain dirt and absorb liquids. However, a problem with current microfiber cleaning pads is that such pads tend to glide over the floor and are thus not effective for scrubbing applications. Floor contractors often use cut pile microfiber for tacking floors. Such pads are highly moisture absorbent. However, such cut pile microfiber pads when used on a floor mop are extremely difficult to push across a floor when the pad is wet.

BRIEF DESCRIPTION OF THE DRAWINGS

FIG. 1 is a bottom plan view an example embodiment of a cleaning pad.

FIG. 2 is a cross-sectional side elevation view of the cleaning pad of FIG. 1 mounted on a mop.

FIG. 3 is a bottom plan view of another example embodiment of a cleaning pad.

FIG. 4 is an isometric view of a floor mop that includes the cleaning pad of FIG. 1.

FIG. 5 is a flow diagram of a method of making a cleaning pad.

FIG. 6 is a flow diagram of another method of making a cleaning pad.

FIG. 7 is a side elevation view of another example embodiment of a cleaning pad.

FIG. 8 is a bottom plan view of an example embodiment of a cleaning bonnet for a rotary floor care machine.

FIG. 9 is a side elevation view of a rotary floor care machine having a cleaning bonnet mounted thereon.

SUMMARY

This specification discloses a cleaning pad having at least one strip of relatively lower absorbency material such as cut pile microfiber; at least one strip of relatively higher absorbency material such as loop microfiber, and at least one strip of scrubbing/bristle material. Embodiments of such a cleaning pad have a combination of features including good scrubbing properties, provided primarily by the scrubbing/bristle material; good wetting of food/dirt/small particles and low friction displacement of the mop head, provided primarily by the relatively lower absorbency material; and good moisture absorption and good food/dirt/small particle capture, provided primarily by the relatively higher absorbency material.

DETAILED DESCRIPTION

FIG. 1 is a bottom plan view an example embodiment of a cleaning pad 10. FIG. 2 is a side elevation view of the cleaning pad 10 mounted on a mop head 32 of a floor mop 30. The mop head 32 may be conventionally attached to a mop handle assembly 34. The cleaning pad 10, as best

2

shown in FIG. 2, has a bottom material layer 11, which makes contact with a floor surface 17 to be scrubbed, and a top material layer 13. The bottom and top layers 11, 13 are connected as by adhesive 15 or by stitching or by other attachment means.

The materials used in the bottom layer include a relatively lower absorbency material and a relatively higher absorbency material. One measure of absorbency is based on the weight of water absorbed by the material after it has been placed in a water bath for a predetermined period of time, for example 10 minutes. The amount of material tested may be specified by the surface area of the tested samples, when all samples tested have approximately the same thickness. Thus in one testing method, the absorbency of the material is expressed in grams of water absorbed per square centimeter of material.

In one example embodiment, for the relatively lower absorbency material, the water absorption per unit area was about 0.226 g/cm². Performing the same test on the strip of relatively higher material, the water absorption per unit area was about 0.308 g/cm². Thus, the relatively higher material had an absorption rate about 1.36 times higher than that of the relatively lower absorbency material. In another embodiment, the relatively higher material had an absorption rate about 1.60 times higher than that of the relatively lower absorbency material.

The top layer 13 of the pad 10 may be a unitary sheet of fabric that may be made from cotton, wool, or a manmade fiber such as nylon, or other backing material. In one embodiment the top layer 13 (sometimes referred to herein as "backing material") has a composition of 100% polyester. As best shown in FIG. 1, the pad bottom layer 11, which may be generally rectangular in shape, has first and second longitudinal edges 16, 18 and first and second lateral edges 20, 22. In some embodiments a strip of fabric material 19, shown in dashed lines, is folded over the bottom and top layers 11 and 13. The strip 19 is attached to the pad at its outer edges 16, 18, 20, 22 by stitching or other attachment means. The bottom layer 13 is composed of multiple laterally extending, parallel strips of material that may be sewn or otherwise connected at the abutting edges thereof. In the example embodiment shown in FIG. 1 the bottom layer 11 is formed by two outer strips of relatively lower absorbency material 24A and 24B, two inner strips of relatively higher absorbency material 26A and 26B and a central strip of scrubbing/bristle material 28.

In one embodiment the scrubbing/bristle material is white nylon bristles, in another it is polyester scrubbers—a stiff, brush like material. However, the bristles could be made from any sufficiently stiff and wear resistant man made material, plant fiber or animal hair. The bristles, as well as improving the scrubbing efficiency of the mop, are very useful when encountering bevel or gout lines where current mops do not perform well. The scrubbing/bristle material has a very low water absorption per unit area. In most example embodiments, the water absorption per unit area is negligible.

The relatively lower absorbency material 24A, 24B could be any of the following materials, or other materials: 100% polyester twist loop microfiber material or 2 Denier 100% polyester 1 ply material.

The relatively higher absorbency material 26A, 26B could be any of the following materials, or other materials: cut pile microfiber, or an 80/20 Polyester/Nylon blend, untwisted composition material or an 80% Polyester, 20% Polyamide, 3 plies material.

In the embodiment of FIG. 1, the relatively lower absorbency material 24A, 24B occupies about 50% of the total surface area, the relatively higher absorbency material 26A, 26B occupies about 40% and the scrubbing/bristle material occupies about 10%. In a slightly different version, the strip layout order is the same, except that the relatively lower absorbency material strips 24A, 24B occupy about 40% of the total surface area, the relatively higher absorbency material strips 26A, 26B occupy about 50% of the total surface area and the scrubbing/bristle material strip 28 occupies about 10% of the total surface area. Other strip area ratios may also be used. The heights of all the strips 24, 24A, 26, 26A and 28 may be the same, such that the bottom surfaces of all the strips are substantially coplanar and all simultaneously engage the floor surface 17, as shown in FIG. 2.

FIG. 3 is a bottom plan view of a cleaning pad 110 of the same type as the cleaning pad 10 shown in FIG. 1, but with a different arrangement of material strips in the bottom layer 111 thereof. In this embodiment a relatively higher absorbency material strip 126 is located at the center of the bottom layer 111. A scrubbing/bristle material strip 128A or 128B is attached to either side of the cut pile strip 126. A relatively lower absorbency material strip 124A and 124B is attached to each of the scrubbing/bristle material strips 128A, 128B, respectively. The area ratios of each strip type may be the same as in the two versions of the cleaning pad 11 described above with reference to FIG. 1, i.e., in a first version the relatively lower absorbency material strips occupy about 50% of the total surface area, the relatively higher absorbency material strips occupy about 40% and the scrubbing/bristle material strip occupies about 10%. In a second version, the relatively lower absorbency material strips occupy about 40% of the total surface area, the relatively higher absorbency material strips occupy about 50% of the total surface area and the scrubbing/bristle material strip occupies about 10% of the total surface area. In the embodiment of FIG. 3, the scrubbing/bristle material strips 128A, 128B may each be about 60 mm wide in both of the different area ratio versions.

One advantage of some embodiments of the cleaning pads illustrated in FIGS. 1-3 is that most consumers using such a cleaning pad on a mop, would be able to push the mop across a wood floor without difficulty.

FIG. 4 illustrates a floor mop 150 having a mop head 152 with an elongate handle 154 attached thereto. A cleaning pad 156, which may be similar or identical to the cleaning pads 10 or 110 described herein, is attached to the bottom of the mop head 152 as by hook and loop fasteners or other attachment means. Thus the floor mop 150 may comprise a mop head 152 having attached thereto a cleaning pad 156. The cleaning pad has at least one strip of relatively lower absorbency material, e.g., strip 24A (FIG. 1), at least one strip of relatively higher absorbency material, e.g., strip 26A (FIG. 1) and at least one strip of scrubbing/bristle material, e.g., strip 28 (FIG. 1).

FIG. 5 is a flow diagram of an example method of making a cleaning pad. The method, in one embodiment, includes, as shown at block 210, attaching a strip of relatively higher absorbency material to a sheet of backing material. The method may also include, as shown at block 212, attaching at least one of a strip of relatively lower absorbency material and a strip of scrubbing/bristle material to the sheet of backing material.

The strips may be linear strips positioned in a parallel relationship as shown in FIGS. 1 and 3. However, the strips may be otherwise arranged, for example, the strips may be

divided into small squares and arranged in a checkerboard pattern (not shown). Also, rather than being linear, the strips could have a snake-like, undulating configurations (not shown), or other configurations.

5 In some embodiments the backing material, e.g. top material layer 13 is eliminated and the various strips of relatively lower absorbency material, relatively higher absorbency material and scrubbing/bristle material are attached at adjacent edges thereof directly to one another, for 10 example, such as shown in FIG. 1 or 3. A side elevation view of such a cleaning pad 300 is illustrated in FIG. 7.

FIG. 6 is a block diagram of another embodiment of a 15 method of making a cleaning pad. The method includes, as shown in block 220, attaching a strip of relatively higher absorbency material to a strip of scrubbing/bristle material. Other methods include the method of FIG. 6 and further steps, for example: attaching a second strip of relatively higher absorbency material to the strip of scrubbing/bristle material and attaching a first and second strip of relatively 20 lower absorbency material to the first and second strips of relatively higher absorbency material, respectively. Still other embodiments include the method of FIG. 6 and further comprise attaching a strip of relatively higher absorbency material to the strip of scrubbing/bristle material; and may 25 further include attaching a second strip of scrubbing/bristle material to the strip of relatively higher absorbency material and may further include attaching a second strip of relatively lower absorbency material to the second strip of scrubbing/bristle material.

30 FIG. 8 is a bottom plan view of an example embodiment of a cleaning bonnet 170 for a rotary floor care machine. The cleaning bonnet comprises a floor engaging face 171 having alternating higher absorbency strips 172 and lower absorbency strips 174 with harder surfaces scrubbing material 35 strips 176 positioned between each pair of higher absorbency strips 172 and lower absorbency strips 174. The higher absorbency strips 172 and lower absorbency strips 174 may be constructed from the same material as described above for the cleaning pad 10 or may be made from other 40 materials. The scrubbing material strips 176 may be made of nylon or other scrubbing material.

FIG. 9 is a side elevation view of a rotary floor care machine 180, such as a buffer having a cleaning bonnet mounted thereon. A sander (not shown) may be substituted 45 for the buffer in some embodiments. The rotary floor care machine 180 has a rotary head 182. The cleaning bonnet 170 has a skirt portion 178 attached to the face 171 as by a seam or material strip 179. The skirt portion 178 encompasses a peripheral portion of the rotatory head. A draw string 175 or 50 elastic band or other securing means provided at the edge of the skirt securely fastens it to the rotating head 182.

Various embodiments of cleaning pads, mop assemblies with cleaning pads and methods of making cleaning pads have been disclosed in detail herein. Alternative embodiments of such cleaning pads, mop assemblies and associated methods will occur to those skilled in the art after reading this disclosure. It is intended that the appended claims be construed broadly to cover such alternative embodiments, except as limited by the prior art.

60 What is claimed is:

1. A cleaning pad comprising: at least one strip of relatively lower absorbency material, at least one strip of relatively higher absorbency material, which is at least about 1.36 times higher absorbency than the relatively lower absorbency material, and at least one strip of scrubbing/bristle material; wherein all of said strips are substantially equal height and form a substantially coplanar floor engag-

ing surface, wherein the floor engaging surface has a total surface area comprising at least about 40% from the lower absorbency material and at least about 40% from the higher absorbency material.

2. The cleaning pad of claim 1 further comprising a sheet of backing fabric and wherein said at least one strip of relatively lower absorbency material, said at least one strip of relatively higher absorbency material and said at least one strip of scrubbing/bristle material are attached to said sheet of backing fabric.

3. The cleaning pad of claim 1, said cleaning pad comprising: two strips of said relatively higher absorbency material, two strips of said relatively lower absorbency material and one strip of said scrubbing/bristle material.

4. The cleaning pad of claim 1, said cleaning pad comprising: one strip of relatively higher absorbency material, two strips of relatively lower absorbency material and two strips of scrubbing/bristle material.

5. The cleaning pad of claim 1 wherein said floor engaging surface total surface area comprising: about 50% lower absorbency material, about 40% higher absorbency material and about 10% scrubbing/bristle material.

6. The cleaning pad of claim 1 wherein said floor engaging surface total surface area comprising: about 40% relatively lower absorbency material, about 50% relatively higher absorbency material and about 10% scrubbing/bristle material.

7. The cleaning pad of claim 3 said scrubbing/bristle material strip having a width of about 120 mm.

8. The cleaning pad of claim 4, each strip of cleaning bristle having a width of about 60 mm.

9. The cleaning pad of claim 1: wherein said relatively higher absorbency material has an absorbency of at least about 1.6 times that of said relatively lower absorbency material.

10. The cleaning pad of claim 1 wherein said relatively lower absorbency material comprises loop microfiber.

11. The cleaning pad of claim 1 wherein said relatively higher absorbency material comprises cut microfiber.

12. The cleaning pad of claim 1 wherein said relatively lower absorbency material comprises a 100% polyester composition.

13. The cleaning pad of claim 1 wherein said relatively higher absorbency material comprises about 80% polyester and 20% nylon.

14. A floor mop comprising a mop head, said mop head having attached thereto a cleaning pad, said cleaning pad having: at least one strip of relatively lower absorbency

material, at least one strip of relatively higher absorbency material that is at least about 1.36 times higher absorbency than the relatively lower absorbency material and at least one strip of scrubbing/bristle material; wherein all of said strips form a substantially coplanar floor engaging surface, wherein the floor engaging surface has a total surface area comprising at least about 40% from the lower absorbency material and at least about 40% from the higher absorbency material.

15. The floor mop of claim 14 wherein said at least one strip of relatively lower absorbency material and said at least one strip of relatively higher absorbency material and said at least one strip of scrubbing/bristle material are attached to a sheet of backing fabric.

16. The floor mop of claim 14, said cleaning pad comprising: two strips of said relatively higher absorbency material; two strips of said relatively lower absorbency material; and one strip of said scrubbing/bristle material.

17. The floor mop of claim 14, said cleaning pad comprising: one strip of said relatively higher absorbency material, two strips of said relatively lower absorbency material and two strips of said scrubbing/bristle material.

18. The floor mop of claim 14 wherein said floor engaging surface total surface area comprising: about 50% relatively lower absorbency material, about 40% relatively higher absorbency material and about 10% scrubbing/bristle material.

19. The floor mop of claim 14 wherein said floor engaging surface total surface area comprising: about 40% of said relatively lower absorbency material, about 50% of said relatively higher absorbency material and about 10% of said scrubbing/bristle material.

20. The floor mop of claim 14: wherein said relatively lower absorbency material has an absorbency of about 0.226 g/cm² and wherein said relatively higher absorbency material has an absorbency of about 0.308 g/cm².

21. The floor mop of claim 14 wherein said relatively lower absorbency material comprises loop microfiber.

22. The floor mop of claim 14 wherein said relatively higher absorbency material comprises cut microfiber.

23. The floor mop of claim 14 wherein said relatively lower absorbency material comprises a 100% polyester composition.

24. The floor mop of claim 14 wherein said relatively higher absorbency material comprises a composition of about 80% polyester.

* * * * *
